5 Claims. (Cl. 53—134)

1

This invention relates to automatic wrapping machinery, and the invention has reference, more particularly, to a novel construction of high speed, continuous motion wrapping machine.

The invention has for an object to provide a novel construction of wrapping machine comprising a continuously rotated wrapping wheel having circumferentially spaced pockets opening outwardly from its periphery for the reception of articles to be wrapped together with wrapper material for enveloping the same, means being provided for automatically inserting articles and wrapper material in successive pockets of the rotating wrapping wheel, means cooperative with the rotating wrapping wheel being further provided for manipulating the wrapper material, whereby to envelop the articles therein, and means being also provided for ejecting the wrapped articles from the pockets of the rotating wrapping wheel.

The invention has for another object to provide means cooperative with the wrapping wheel and the means for inserting articles into the pockets of said wheel whereby to deliver wrapper material for application to each article delivered to and inserted within the wrapping wheel pockets.

Another object of the invention is to provide in connection with the pockets of the wrapping wheel means for firmly gripping and holding the articles and wrapper material entered therein against displacement and subject to the operations of wrapper material folding devices which cooperate with the rotating wrapping wheel.

Other objects of this invention, not at this time more particularly enumerated, will be understood from the following description of the same.

An illustrative embodiment of the invention is shown in the accompanying drawings, in which:

Fig. 1 is a side elevational view with parts in section showing the wrapping machine of this invention.

Fig. 2 is a fragmentary horizontal sectional view taken on line 2—2 in Fig. 1, but drawn on an enlarged scale, showing the initial position of means for inserting an article together with wrapper material into a pocket of the wrapping wheel; and Fig. 3 is a vertical longitudinal sectional view, taken on line 3—3 in Fig. 2.

Fig. 4 is a view similar to that of Fig. 2, but showing the position of the means for inserting an article together with wrapping material into a pocket of the wrapping wheel as disposed at the end of its operative stroke; and Fig. 5 is a

2

vertical longitudinal sectional view, taken on line 5—5 in Fig. 4.

Fig. 6 is a fragmentary vertical sectional view of the wrapping wheel and associated parts cooperative therewith to produce initial folds of the wrapper material about an article carried in a wrapping wheel pocket.

Fig. 7 is a fragmentary side elevation view of means cooperative with the wrapping wheel to produce initial end folds of the wrapper material about the carried article; Fig. 8 is a top plan view of said initial end fold producing means as positioned in Fig. 7; and Fig. 9 is a view similar to that of Fig. 7 showing an advanced position of said initial end fold producing means.

Fig. 10 is a fragmentary side elevational view of means cooperative with the wrapping wheel to produce further end folds of the wrapper material about the carried articles.

Fig. 11 is a fragmentary side elevational view of means cooperative with the wrapping wheel for completing the end folds of the wrapper material about the carried article; and Fig. 12 is a horizontal sectional view of the same, taken on line 12—12 in Fig. 11.

Fig. 13 is a fragmentary side elevational view of means for ejecting wrapped articles from the pockets of the wrapping wheel.

Similar characters of reference are employed in the above described views, to indicate corresponding parts.

Referring to the drawings, the illustrative embodiment of this invention shown thereby is sized and designed for wrapping candy pieces or tablets or similar articles, but it will be understood that, without substantial departure from design and mode of operation, the machine may be readily adapted to wrap other kinds of three dimensional articles.

The wrapping machine according to this invention comprises a wrapping wheel mounted on a shaft 21. Said wrapping wheel and its shaft is adapted to be continuously rotated by suitable power transmission means (not shown).

The wrapping wheel, in a preferred form thereof as shown, comprises a pair of wheel members 22 which are fixed on the shaft 21 in laterally spaced apart relation, the spacing being such as to conform to the length or width, as the case may be, of articles to be operated upon. Provided in the peripheries of the wheel members 22 are a plurality of indenting, circumferentially spaced pocket forming notches 23, the depths of which are such as to conform to the thickness of the articles to be operated upon. Corresponding

pocket forming notches 23 of the respective wheel members are disposed in transverse alignment, whereby to cooperate in forming a series of equi-spaced article and wrapper material receiving pockets around the wrapping wheel circumference. Each wheel member 22 is provided with radial slots 24 which respectively border corresponding sides of the respective pocket forming notches 23.

Pivotedly supported on the respective outer ends of transverse fulcrum pins 25, which are mounted to extend through and between the wheel members 22 inwardly of or behind the inner ends of the radial slots 24, are gripper members 26. Said gripper members are thus mounted on the external faces of the wheel members 22. Each gripper member 26 is provided with an outwardly extending, inwardly offset gripper jaw 27 which is housed in a slot 24 so as to oppose one side of a pocket forming notch 23 to which it is contiguous. The slots 24, in which said gripper jaws are housed, are of widths exceeding the widths or thicknesses of said gripper jaws 27, whereby the latter may swing toward and from the pockets, being yieldably urged toward the latter by compression spring elements 28. Said compression spring elements 28 are supported in sockets 29 formed in the bodies of the gripper jaws to open toward slot sides opposed to the sockets in the faces of said gripper jaws 27.

Opposed to the wrapping wheel, in the plane thereof but spaced a suitable distance from the periphery thereof, is means for delivering articles to be wrapped subject to transfer to and insertion into the pockets of said wrapping wheel. One illustrative form of said delivery means as shown comprises a rotated delivery wheel 30 which is mounted on a drive shaft 31. The periphery of said delivery wheel 30 is provided with a circumferential channel 32 of suitable depth and of a width conforming to the length or width, as the case may be, of articles to be operated upon. Running over the periphery of said delivery wheel 30, within the channel 32 thereof, is a conveyer belt 33, the top or receiving course of which advances to the delivery wheel through a correspondingly channeled loading table 34. The articles to be operated upon are passed from a supply thereof, deposited upon the surface of the loading table 34, into the channel of the latter so as to lodge on and form a train thereof upon the conveyer belt 33, whereby to be advanced with the latter over the delivery wheel.

Cooperative with the delivery wheel 30 and the conveyer belt 33 thereon is means adapted to remove the articles from said conveyer belt for delivery to a transfer means which successively carries the same to and inserts them into successive pockets of the wrapping wheel. The means for thus removing articles from the conveyer belt 33 comprises a stationary chute 35 which is suitably supported intermediate the delivery wheel and the wrapping wheel. The upper or receiving end portion 35' of said chute curves inwardly toward the delivery wheel so that its extremity is in contact with the periphery of said delivery wheel and with the surface of the conveyer belt 33 substantially tangential thereto and in descending extension therefrom. The lower or discharge end portion 36 of the chute terminates above a transfer mechanism which is mounted to oscillate between the delivery wheel and the wrapping wheel. The ar-

ticles advanced by the conveyer belt 33, upon arrival at the chute, are deflected by the receiving end portion of said chute so as to be removed from the conveyer belt, and thence to move, under gravity, downwardly through to chute to the transfer mechanism.

The transfer mechanism is a very important part of this mechanism, since by its oscillations, which are automatically controlled in timed relation to the movement of the pockets of the continuously rotated wrapping wheel to a predetermined article receiving point, the articles to be wrapped are not only carried to the wrapping wheel but are successively inserted in successive pockets thereof without necessity for interrupting its continuous rotary motion. Said transfer mechanism comprises an oscillator arm 37 carried by a rock-shaft 38 so as to extend upwardly between the delivery wheel and the wrapping wheel. The oscillatory movements of said oscillator arm 37 are produced and properly timed by a rotated control cam 39 which actuates a crank-arm 40 that is affixed to and extends from said rock-shaft 38; said crank-arm having an anti-friction roller 41 which engages the periphery of said control cam. The roller 41 of the crank-arm 40 may be caused to yieldably follow the control cam 39 by any suitable means. One illustrative form of means for this purpose, as shown, comprises a rocker member 42 which is pivotally mounted in connection with a supporting or bearing standard 43. One arm 44 of said rocker member 42 yieldably thrusts upon an anti-friction roller 45 of a keeper lever 46, which extends from the rock-shaft 38, under the urge of compression spring means 47 which is operative upon the opposite arm 48 of said rocker member.

The article delivered to the transfer mechanism, in the illustrative embodiment of the invention as shown, comprises a candy piece C, and will be so referred to hereinafter for convenience of description but without limiting intent. The upper or free end of the oscillator arm 37 is provided with means for supporting a candy piece C, whereby to carry the same to the wrapping wheel, and thereupon insert the candy piece into a receiving pocket of the latter. Said means is best shown in Figs. 2 to 5 inclusive of the drawings, wherein, for better illustration and understanding of its mode of operation, the movement of said means is shown as if in rectilinear plane rather than in the actual arcuate plane as occurs in practice, and which will be obvious from an inspection of Fig. 1. Said means comprises a head portion 49 in which the upper end of the oscillator arm 37 terminates. Integral with and above said head portion 49 is an impeller member 50, the forward end portion 51 of which projects freely beyond the head portion 49. Said impeller member 50 substantially corresponds in width to the width or length, as the case may be, of the candy piece C, and terminates at its forward extremity in a thrust face 52 which is operative to abut a candy piece so as to forwardly propel the same toward the wrapping wheel during forward swinging movement of the oscillator arm 37. Beneath the impeller member 50, said head portion 49 is provided in its opposite side faces with longitudinal guide channels or ways 53. Mounted beneath said impeller member 50, subject to longitudinal movements relative thereto, is a platform plate 54 provided with a bifurcate rear end portion, the legs 55 of which straddle the head portion 49 so as to be respec-

tively slidably supported in said guide channels or ways 53. The platform plate is of a width substantially exceeding the widths of the head portion 49 and impeller member 50. Adjacent to its forward extremity, said platform plate 54 is provided with upstanding keeper lugs 56 which are so spaced, transversely of the platform plate, as to straddle the impeller member 50 and a candy piece C, when said candy piece is deposited upon said platform plate in front of the impeller member, whereby to retain said candy piece in alignment with the latter. Pivotally connected with the platform 54, at points adjacent to its rearward end so as to respectively extend forwardly along the underface of said platform plate and respectively exteriorly of the opposite sides of the head portion 49 and impeller member 50, are a pair of laterally swingable gripper elements 57. The forward end portions of the gripper elements 57 terminate in outwardly offset, upwardly projecting arms 58 which, in turn, terminate in forward extensions 59 disposed in a plane above the top surface of the platform plate 54. Connected with the outer ends of said extensions 59 are inwardly and laterally projecting gripper jaws 60, which cross in front of the aforesaid keeper lugs 56. The free ends of said gripper jaws 60 terminate in chamfered jaw faces 61. The side marginal portions of the platform plate 51 are cut away at 62 to provide clearance for the arms 58 of said gripper elements. Dependent from the under face of the platform plate 54, at the respective opposite sides thereof and exteriorly of the rearward portions of said gripper elements 57, are abutment lugs 63 to purchase compression springs 64 for yieldable in-swinging thrust upon said gripper elements. Said gripper elements 57 straddle the head portion 49, and are provided on their inner sides, for normal disposition in front of the forward end of said head portion when the platform plate 54 occupies its forwardly disposed candy piece supporting position, with cam portions 65. Said cam portions 65 are adapted to be engaged by said head portion, when the platform plate 54 is rearwardly moved relative thereto and to said impeller member 50, whereby to induce outswinging movements of the gripper jaws 60 from initial holding relation to a candy piece C which is supported by the advanced platform plate in front of said impeller member 50. The platform plate 54 is provided with means for controlling and timing its longitudinal movements relative to the head portion 49 and impeller member 50. This means includes a stop ear 66 disposed to project laterally from the rearward end portion of the platform plate at one side thereof and preferably at both sides thereof. Dependent from the discharge end portion 36 of the chute 35, at one or both sides thereof as the case may be, is a stop finger 67 with which a stop ear 66 of the platform plate 54 cooperates at proper times, as will presently appear.

By its rearward swinging movement, the oscillator arm 37 carries the head portion 49 and impeller member 50 into stopped relation contiguous to the delivery wheel 30, during which movement the rear end of the then retracted platform plate 54 is carried into engagement with the periphery of the delivery wheel 30, so that rearward movement of said platform plate, in company with the head portion 49 and impeller member 50, is arrested while rearward movement of the head portion and impeller member continues. This results in a forward sliding move-

ment of the platform plate relative to the head portion and impeller member, whereby the forward end portion of the platform plate is projected beyond the thrust face 52 of the impeller member 50, being thus disposed to receive and support a candy piece C deposited thereon from the chute 35.

It will be understood that the top face of the impeller member 50, as it moves beneath the mouth of the discharge end of the chute 35, operates as detent means for holding candy pieces contained in the chute against discharge.

As the platform plate 54 is advanced to candy piece receiving and supporting position, the rearward movement of the impeller member 50 will carry its thrust face 52 past the discharge mouth of the chute 35, so that a candy piece C may drop from the latter onto the platform plate 54 between the keeper lugs 56 and in front of said thrust face 52 of the impeller member. By the time the candy piece is so deposited, the cam portions 65 of the gripper elements 57 will be disengaged by the rearwardly moving head portion 49, thus permitting said gripper elements to swing inwardly under the impulsion of their springs 64, and thereby to close the gripper jaws 60 in holding relation to the deposited candy piece. The transfer mechanism being thus loaded is ready to make its ensuing swing toward the wrapping wheel, whereby to deliver the carried candy piece thereto (see Figs. 2 and 3).

Means is provided for delivering wrapper material between the retracted transfer mechanism and the wrapping wheel. The wrapper material may be of any suitable kind, such e. g. as transparent cellulose or cellophane, waxed paper or ordinary paper. It is preferable to supply the wrapper material, which is indicated by the reference character W, in the form of a continuous web of suitable width adapted to be drawn from a suitably positioned supply roll 68 by a pair of feed rollers 69, through the nip of which the web is passed. From the feed rollers 69, the wrapper material passes through cutting means which, as illustratively shown, comprises a stationary knife 70 and a rotary knife 71 which is cooperative therewith. The rotary knife 71 is driven in suitably timed relation to the coordinated movements of the wrapping wheel and transfer mechanism, so as to sever from the web a section of the wrapper material which is adapted to provide an individual wrapper subject to engagement between a candy piece C as advanced by the transfer mechanism and means for holding the wrapper relative to said candy piece until the latter and said wrapper are ultimately together inserted in a receiving pocket of the wrapping wheel. The means for thus holding the wrapper in engagement with an advancing candy piece comprises a pivoted retainer member 72 which extends through the space intermediate the side sections of the wrapping wheel so that its gripping nose 73 is opposed to the candy piece C which is carried and advanced by the transfer mechanism. Said retainer member 72 is yieldably outswung to normally project its gripping nose 73 beyond the periphery of the wrapping wheel, and to this end is controlled by a crank arm 74 to which is connected a pull spring 75 75 (see Fig. 1).

As arranged for coordinated relative movements, as a receiving pocket of the continuously rotated wrapping wheel moves toward a point opposite the transfer mechanism the forward movement of the latter is occurring, so that a

candy piece C is advanced toward the wrapping wheel. The advancing candy piece first engages the wrapper, so that the latter is pushed against the gripping nose 73 of the yieldable retainer member 72, at which moment the wrapper section is severed from the web of wrapper material by the cutting means 70—71. The transfer mechanism is timed to complete its candy piece advancing stroke at the moment a receiving pocket of the wrapping wheel reaches alignment with and opposes the candy piece, and consequently the impeller member 50 of the transfer mechanism pushes the candy piece, together with the wrapper into said receiving pocket (see Figs. 4 and 5). Just before the candy piece is thus entered in a receiving pocket of the wrapping wheel, and before the advancing movement of the head portion 49 and impeller member 50 is completed, the stop ear means 66 of the then advanced platform plate 54 abuts the stationary stop finger means 67, thus arresting forward movement of the platform plate in company with the head portion 49 and impeller member 50, which results in a retractive sliding movement of the platform plate relative to these parts, thus withdrawing said platform plate from its initially advanced position. Thereafter continued forward movement of the head portion 49 passes the same between and into engagement with the cam portions 65 of the gripper elements 57, thereby outswinging the latter so as to withdraw the gripper jaws 60 from the candy piece C and out of the path of movement of said candy piece as it continues to move on under the propulsion of the impeller member 50, and ultimately into a receiving pocket of the wrapping wheel (see Fig. 4). Such arresting of the platform plate 54 also restrains the same from engaging or interfering with the rotating wrapping wheel, and allows the impeller member 50 to advance freely beyond the forward end of the platform plate so as to remove the candy piece therefrom, and thereupon complete propulsion of the candy piece into a receiving pocket of the wrapping wheel (see Figs. 4 and 5). Immediately the candy piece and wrapper therefor is thus deposited in a receiving pocket of the wrapping wheel, the transfer mechanism is retracted to initial back swung position, whereby to condition the same for the reception and support of another candy piece, in the manner already hereinabove described, ready to be advanced and delivered to a succeeding receiving pocket of the wrapping wheel by repetition of the operations immediately above described.

It will be understood that the tensionally yieldable gripper jaws 27 which border each receiving pocket of the wrapping wheel will yield to the entrance of candy pieces and associated wrappers into said receiving pockets. Said yieldable gripper jaws 27 not only accommodate the receiving pockets in compensation for any slight variations which may occur in size of the candy pieces, but also, by their tensional thrust, serve to grip the candy pieces and wrappers between pocket walls, so as to firmly and securely hold the same against accidental shift in or displacement from the pockets.

It will be obvious that, as a candy piece entering a receiving pocket of the wrapping wheel pushes the wrapper therewith into said pocket the wrapper will be initially folded about the back and sides of the candy piece which are contiguous to the pocket walls, and that front flaps of the wrapper, viz. a trailing front flap f and a

leading front flap f', will project radially in extension from the periphery of the wrapping wheel, while end portions e of the wrapper will project laterally outward in extension from the external sides of the wrapping wheel.

After the candy piece with its wrapper is deposited in a receiving pocket of the wrapping wheel, said candy piece and wrapper assembly is moved by the rotation of the wrapping wheel 10 so as to successively pass various means whereby the folding of the wrapper entirely about the candy piece is accomplished. Preparatory to movement relative to said various wrapper folding means, a down-folding of the trailing front flap f of the wrapper over the outer face of the deposited candy piece is effected. The means for thus down-folding said trailing front flap f comprises a folding blade 76 which is carried at the end of an oscillatable lever member 77, so 15 as to extend transversely across the periphery of the wrapping wheel above the point occupied by a receiving pocket thereof at which a candy piece with its wrapper is entered in said pocket. Said lever member 77 is pivoted to swing about the axis of rotation of the wrapping wheel, and its oscillations are produced and properly timed by a rotating cam wheel 78. Said lever member 77 is provided with an angularly extending arm 79 having an anti-friction roller 80 which rides 20 upon the periphery of said cam wheel 78, whereby to effect the operative movements of said lever member 77 and folding blade 76 carried thereby.

Immediately the candy piece with its wrapper 35 is deposited in a receiving pocket of the wrapping wheel, the folding blade 76 is timed to make an operative down stroke which carries it against the trailing front flap f so as to swing down said flap, and thus fold it flatly against and 40 across the outer face of the candy piece (see Fig. 6).

Extending for a suitable distance along and contiguous to the periphery of the wrapping wheel, from a point adjacent that at which a 45 pocket of the latter receives a candy piece with its wrapper, is a stationary combined folding and keeper plate 81, the width of which substantially corresponds to the width of the wrapping wheel. As the candy piece is carried along by the rotation of the wrapping wheel beneath said folding and keeper plate 81, the leading front flap f' will be moved against the forward end thereof so as to be turned over thereby flatly across the outer face of the candy piece, and 50 55 so as to lap the previously folded trailing front flap f (see Fig. 6). It will be understood that, as movement of the candy piece and wrapper relative to said stationary folding and keeper plate 81 continues, said plate serves to retain said flaps f and f' in their described folded relation to the candy piece, while the ends e of the wrapper project beyond the lateral margins of said folding and keeper plate, so as to be engageable by means operative to form the necessary tucks and folds therein by which the ends of the candy piece are embraced and covered.

Bordering the folding and keeper plate 81, in a selected advanced position beyond the point at which a pocket of the wrapping wheel receives a candy piece with its wrapper, is means 70 for tucking and down folding the trailing sides of the laterally extending ends e of the wrapper. This means comprises revolving arms 82 respectively disposed adjacent each side of the wrapping wheel, so as to revolve in planes par-

allel to that of the wrapping wheel. Said arms 82, as viewed in Figs. 1, 7 and 9, revolve in counter-clockwise direction, and thus oppositely to the rotation of the wrapping wheel, which is in clockwise direction as viewed in the same figures. Affixed to each revolving arm 82, at a side thereof which opposes the adjacent face of the wrapping wheel, is a tucker finger 83. Said tucker finger 83 lies in a plane substantially parallel to the plane of the adjacent face of the wrapping wheel, and projects forwardly, i. e. in the direction of rotation of the arm 82. Also affixed to each revolving arm 82 is a folder finger 84, which also projects forwardly, i. e. in the direction of rotation of the arm 82. Said folder finger 84 lies in substantially the same plane as that of the tucker finger 83, but is suitably outwardly spaced and somewhat rearwardly offset therefrom, so that its folding effect upon a wrapper end e occurs subsequent to the tucking effect of the tucker finger 83 upon said wrapper end e.

As a candy piece and associated wrapper is carried by the wrapping wheel past the revolving arms 82, the speed of revolution of the latter is so timed relative to the rotary progress of the wrapping wheel that the tucker fingers 83 are rapidly carried against the trailing sides of the projecting wrapper ends e so as to first tuck inward the vertical faces thereof against the adjacent end of the candy piece (see Fig. 7). Following this, the continuing revolution of the arms 82 carries the folder fingers 84 over and downwardly against the horizontally extending portions of the wrapper ends e at points adjacent to the trailing sides of the latter, thereby down folding these portions of the wrapper ends relative to the ends of the candy piece (see Fig. 9). These operations leave the leading sides of the wrapper ends e still in somewhat outwardly projecting extension (again see Fig. 9).

Beyond the above described revolving tucking and folding means, additional means is provided for completing the in-folding and down-folding of the leading sides of the wrapper ends e. This latter means comprises suitably supported stationary folder plates 85 which lap the external side marginal portions of the wrapping wheel and the forward end portion of the folding and keeper plate 81 in suitably spaced contiguous relation thereto. Each folder plate 85 is provided at its rearward end with a downwardly and forwardly inclined vertical plow portion 86, which preferably terminates at its upper or inner end in a rearwardly projecting undercut nosing 87; the latter being so disposed as to intersect and overhang the plane of the bottom of a receiving pocket of the wrapping wheel, when said pocket is advanced by rotation of the wrapping wheel past the rearward end of said folder plate 85.

After the candy piece and associated wrapper, as advanced by the wrapping wheel, leaves the revolving tucking and folding means, the leading sides of the wrapper ends e are carried into engagement with the folder plates 85 so as to pass beneath the nosings 87, and thence in passing engagement with the plow portions 86 and behind the bodies of said folder plates, all whereby said leading sides of the wrapper ends e are both in-turned and down-turned to extend somewhat diagonally across and in parallel plane relative to the ends of the candy piece, and so as to lap the previously down-folded portions of the trailing sides of said wrapper ends e, thus leaving free

end portions or tabs t of the folded wrapper material projecting beyond the ends of the candy piece and right angularly to the outer face plane thereof (see Fig. 10).

- 5   5   Provided in connection with the forward end portions of said folder plates 85, so as to extend therebetween in curved plane corresponding to the curvature of the wrapping wheel periphery, and disposed so as to be spaced contiguous to the latter, is a wrapper tab end folder plate 88. Said tab end folder plate 88, as thus bridging between the folder plates 85, may be formed, if desired, to be integral therewith. Said tab end folder plate 88 begins adjacent to the forward end of the folding and keeper plate 81. The rearward portion of the tab end folder plate 88, which opposes the adjacent end of the folding and keeper plate 81, is shaped to provide an open substantially V-shaped mouth 89, the sides of which are formed to provide chamfered turn-over plow sections 90 which converge upon the medial line or axis of the tab end folder plate body (see Fig. 12).

25   After the down-folded tab ends t of the wrapper have been formed, advance of the thus partially wrapped candy piece by the wrapping wheel carries said tab ends respectively into passing engagement with the respective turn-over plow sections 90, by which the same are up-swung and 30   in-turned to overlie the outer face of the candy piece and the enclosing lapped wrapper folds f and f', thereby completing the wrapper folding operations (see Fig. 11). The thus folded tab ends t are carried on beneath the body of the 35   plate 88, so as to be held thereby in their folded positions.

40   Means is provided for sealing down the folded tab ends t. Means for this purpose may be various in kind and location according to the particular character of wrapper material employed. In the illustrative embodiment of the machine of this invention as shown, the sealing means is of a kind and is so located as to operate upon heat sealable wrapping material, such e. g. as cellophane, which is the preferred kind of wrapping material. The sealing means therefore, as shown (see Fig. 1), is located adjacent to forward terminus of the tab end folder plate 89, and comprises an electrically heated sealing iron 91 which is adapted to be brought in contact with the folded tab ends t, so that the heat applied to the latter will thereby cause said tab ends to adhere to the underlying wrapper folds f and f'. Preferably said sealing iron is pivoted on a support 55   92 so that, by suitable actuating means (not shown), it may be swung inward for momentary pressure contact with the wrapped candy piece passing thereunder, and thereafter relaxed.

60   Extending along the periphery of the wrapping wheel, from said sealing means to a point adjacent that at which wrapped candy pieces are to be discharged from the pockets of said wrapping wheel, is a keeper plate 93.

65   Means is provided for automatically discharging the wrapped candy pieces, as the pockets of the wrapping wheel containing the same arrive at a predetermined point in the orbit of the wheel periphery. Said means, in one illustrative form thereof as shown, comprises an oscillatable ejector member 94 which is pivotally suspended from a stationary bracket 95, so that its free end portion extends downwardly between the wrapping wheel members 22, and normally behind a receiving pocket of the wrapping wheel where it 70   75   passes the predetermined discharge point in the

11

wrapping wheel orbit. Extending outwardly, at said predetermined discharge point, from the wrapping wheel periphery is a channeled runway 96 into which the ejected wrapped candy pieces are successively discharged. Suitable means is provided for producing timed oscillation of said ejector member 94, which, illustratively, comprises a reciprocable link 97 having at its rearward end a slotted head 98 slidably supported on a guide block 99, which is, in turn, immovably supported on a shaft 100 by which an actuating cam 101 is rotated. The cam 101 bears against a thrust stud in the form of an anti-friction roller 102, which is mounted on the head 98 of the reciprocable link. A compression spring 103 mounted between the outer end of the head 98 and the guide block 99 causes the roller 102 to follow the cam 101, so that desired reciprocation of the link 97 by the latter is assured. It will be understood that any other suitable means may be provided whereby to cause the link 97 to follow the cam subject to the reciprocating effect thereof. The outer end of the reciprocable link 97 is pivotally connected with a pivoted rocker arm 104, to which is also pivotally connected one end of a connecting link 105. The opposite or outer end of said connecting link 105 is pivotally connected with the ejector member 94 so as to impart its movement thereto, and thus effect timed oscillation of said ejector member. In operation, as a receiving pocket of the wrapping wheel approaches the point at which it is desired to discharge a wrapped candy piece therefrom, said wrapped candy piece will be carried in front of the retracted ejector member 94 (see Fig. 1), and as said discharge point is reached, the ejector member actuating mechanism is timed to cause a forward swing of said ejector member, whereby the latter engages and pushes the wrapped candy piece out of the wrapping wheel pocket and deposits it within the runway 96 (see Fig. 13), the ejector member being thereupon immediately retracted to normal initial position. These operations are repeated as each wrapped candy piece containing pocket reaches the said discharge point in the wrapping wheel orbit.

From the above description it will be apparent that the machine of this invention is of the continuous rotary type, wherein the wrapper folding manipulations are performed by agencies lying adjacent to the orbit of the peripheral portions of the wrapping wheel, and are operative without necessity for interrupting the rotary motion of the wrapping wheel. It will also be apparent that the means for introducing into the wrapping wheel pockets the articles to be wrapped together with wrapper material therefor is so devised that it also functions in a positive and rapid manner likewise without necessity for interrupting the rotary motion of the wrapping wheel. It will therefore be understood that a very compact and yet rapid and efficient wrapping machine is provided by this invention.

We are aware that many changes could be made in the described mechanisms and details of construction thereof as shown in the accompanying drawings without departing from the scope of this invention as defined by the following claims. It is therefore intended that all matter contained in the foregoing description or shown in the accompanying drawings shall be interpreted as illustrative and not in a limiting sense.

We claim:

1. In a wrapping machine having a continuously rotated wrapping wheel provided with cir-

12

cumferentially spaced pockets opening radially and laterally from the peripheral portions thereof for the reception of articles to be wrapped and wrappers therefor, together with means for producing longitudinal folds of the wrapper over an article lodged in a wrapping wheel pocket; the combination with said wrapping wheel of wrapper folding means bordering opposite side marginal portions thereof operative to fold the remaining laterally projecting wrapper portions about the articles, said latter means comprising revolvable arms adapted to be rotated in planes parallel to and respectively adjacent opposite sides of the wrapping wheel, each arm having a leading tucker finger and a following folder finger outwardly and rearwardly offset from said tucker finger, said tucker fingers being adapted to first tuck in trailing sides of the laterally projecting wrapper portions and said folder fingers being thereafter adapted to fold down said wrapper portions across the ends of the article, and stationary means disposed beyond said arms adjacent the sides and periphery of the wrapping wheel operative to fold the leading sides of said laterally projecting wrapper portions over the tucked and down-folded trailing sides of the latter, said last mentioned means including additional means adapted to turn the free end portions of the thus formed wrapper folds inwardly across the outer face of the wrapped article.

2. In a wrapping machine having a continuously rotated wrapping wheel provided with circumferentially spaced pockets opening radially and laterally from the peripheral portions thereof for the reception of articles to be wrapped and wrappers therefor, together with means for producing longitudinal folds of the wrapper over an article lodged in a wrapping wheel pocket; the combination with said wrapping wheel of wrapper folding means bordering opposite side marginal portions thereof operative to fold the remaining laterally projecting wrapper portions about the articles, said latter means comprising revolvable arms adapted to be rotated in planes parallel to and respectively adjacent opposite sides of the wrapping wheel, each arm having a leading tucker finger and a following folder finger outwardly and rearwardly offset from said tucker finger, said tucker fingers being adapted to first tuck in trailing sides of the laterally projecting wrapper portions and said folder fingers being thereafter adapted to fold down said wrapper portions across the ends of the article, stationary folder plates beyond said arms respectively adjacent to opposite side marginal portions of the wrapping wheel in planes parallel thereto, said folder plates being operative to fold the leading sides of said laterally projecting wrapper portions over the tucked and down-folded trailing sides of the latter, and another stationary folder plate disposed adjacent and parallel to the wrapping wheel periphery, said last mentioned folder plate having convergent plow sections operative to turn the free end portions of the formed wrapper folds inwardly across the outer face of the wrapped article.

3. In a wrapping machine as defined in claim 2, means to successively eject the wrapped articles from the wrapping wheel pockets.

4. In a wrapping machine as defined in claim 3, including an article delivery chute opposed to the wrapping wheel, and an oscillatable article transfer means movable between the chute and wrapping wheel operative to insert articles received from said chute together with wrappers therefor

successively into successive pockets of the wheel while the latter is in motion.

5. In a wrapping machine as defined in claim 1, means to successively eject the wrapped articles from the wrapping wheel pockets.
